John Smith, Kathwood, S. C.

Application November 7, 1949, Serial No. 5,908

Term of patent 14 years

(Cl. D71—1)

To all whom it may concern:

Be it known that I, John Smith, a citizen of the United States of America, residing at Kathwood, in the county of Aiken and State of South Carolina, have invented a new, original, and ornamental Design for a Boat, of which the following is a specification, reference being had to the accompanying drawing, forming a part thereof, wherein:

Fig. 1 is a top plan view of a boat, illustrating my new invention;

Fig. 2, a side elevational view;

Fig. 3, a front elevational view;

Fig. 4, a rear elevational view; and

Fig. 5, a longitudinal sectional view.

I claim:

The ornamental design for a boat, as shown.

JOHN SMITH.
